UNITED STATES PATENT OFFICE.

JOSEPH VILARDO, OF BUFFALO, NEW YORK.

SASH-LOCK.

1,287,529.

Specification of Letters Patent. Patented Dec. 10, 1918.

Application filed June 14, 1918. Serial No. 240,017.

To all whom it may concern:

Be it known that I, JOSEPH VILARDO, a citizen of the United States, residing at Buffalo, in the county of Erie and State of New York, have invented new and useful Improvements in Sash-Locks, of which the following is a specification.

This invention relates to sash locks and it consists in the novel features hereinafter described and claimed.

An object of the invention is to provide a sash locking device of simple and durable structure, one which may be easily and quickly manipulated to secure the sash or release the same.

With this object in view the lock comprises a bolt slidably mounted in the casing which holds the sash and adapted to engage in a socket provided at the edge of the sash. A spring is operatively connected with the said bolt for holding the same in a protracted position with relation to the casing. A lever mechanism is mounted in the casing and is adapted to be manipulated to move the bolt to a retracted position whereby its ends will disengage the socket in the sash.

In the accompanying drawing:

Figure 1 is a cross sectional view through a sash and window casing, showing my device applied,

Fig. 2, is a fragmentary front elevation. As illustrated in the accompanying drawing, the sash 1 is provided at its edge with a series of notches or sockets 2. The sash 1 is mounted for movement in a casing 3 and in the usual manner. A bolt 4 is slidably mounted in the casing 3 and its end portion is adapted to enter one of the notches 2 when the sash is held at a locked position with relation to the casing. A spring 5 is housed within the casing 3 and one end of the said spring is connected with the casing and the other end thereof with the bolt 4. The spring 5 is under tension with a tendency to normally hold the end portion of the bolt 4 projected beyond the edge of the casing 3 and toward the sash 1.

As clearly illustrated in Fig. 1 a pulley 6 is journaled within the casing 3 and a lever 7 is fulcrumed within the casing. A flexible chain 8 is connected at one end with the bolt 4 and at its other end with one

end of the lever 7. The intermediate portion of the chain 8 is trained around the pulley 6. Consequently it will be seen that when the lever 7 is swung the chain 8 is moved longitudinally whereby the bolt 4 is withdrawn or moved to a retracted position with relation to the casing 3 and against the tension of the spring 5.

A rod 9 is pivotally connected at its inner end with one end of the lever 7 and the said rod passes through the sides of the casing 3. A knob 10 is journaled on the rod 9 and the said knob is provided at its side with a lug 11 adapted to enter a recess 12 provided in the casing 1 whereby the said knob 10 and the rod 9 are held against longitudinal movement.

When the knob 10 is turned upon the rod 9 so that the lug 11 is moved out of the recess 12 the knob and rod may be moved longitudinally consequently means are provided for swinging the lever 7. When the knob 10 is turned upon the rod 9 so that the lug 11 enters the recess 12 the parts are locked against the movement just stated.

It is apparent that when the sash has been adjusted in the casing 3 the sash may be held at the adjusted position by permitting the end of the bolt 4 to enter one of the notches 2. When it is desired to move the sash this may be accomplished by manipulating the lever whereby the end of the bolt is withdrawn from the notch in the edge of the sash.

Having described the invention what is claimed is:

In combination with a sash movably mounted in a casing, a sash lock comprising a bolt slidably mounted in the casing, a spring for normally holding the bolt in projected position with relation to the casing, a lever fulcrumed in the casing, a pulley journaled in the casing, a chain connected at one end with the bolt and at its other end with the lever and having its intermediate portion trained around the pulley, a rod connected with the lever, a knob journaled upon the rod and having a lug, the said casing having a recess adapted to receive the said lug.

JOSEPH VILARDO.
